(57) **CLAIM**

The ornamental design for an adjustable strap with handles for lifting objects safely, as shown and described.

DESCRIPTION

FIG. 1 is an environmental view of the adjustable strap with handles for lifting objects safely showing my new design;

FIG. 2 is a perspective view of the handle and a portion of the strap;

FIG. 3 is a perspective view of the clip and a portion of the strap;

FIG. 4 is a front elevational view of the strap;

FIG. 5 is a rear elevational view thereof;

FIG. 6 is a side elevational view thereof, with the opposite side being a mirror image;

FIG. 7 is a top plan view thereof;

FIG. 8 is a bottom plan view thereof;

FIG. 9 is a front perspective view of the handle portion, removed for clarity of disclosure;

FIG. 10 is a rear perspective view thereof;

FIG. 11 is a front elevational view thereof;

FIG. 12 is a side elevational view thereof; with the opposite side being a mirror image;

FIG. 13 is a top plan view thereof;

FIG. 14 is a rear elevational view thereof;

FIG. 15 is a bottom plan view thereof;

FIG. 16 is a front perspective view of the clip portion, removed for clarity of disclosure;

FIG. 17 is a rear perspective view thereof;

FIG. 18 is a front elevational view thereof, with the opposite side being a mirror image;

FIG. 19 is a side elevational view thereof, with the opposite side being a mirror image; and,

FIG. 20 is a top plan view thereof.

The broken line showing of a person and a container in FIG. 1 is included for the purpose of illustrating the environment and use of the adjustable strap with handles for lifting objects safely and forms no part of the claimed design.

The dashed lines shown in FIGS. 4 and 5 represent conventional stitching.
